(57) **CLAIM**

The ornamental design for a makeup case, as shown and described.

DESCRIPTION

FIG. 1 is a front, right, and top perspective view of a makeup case, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a part of side walls.

FIG. 10 is a partial enlarged view of an area labeled 10 in FIG. 1 comprising a left upper corner of a body of the makeup case; and,

FIG. 11 is a front, right, and top perspective view of the makeup case of FIG. 1 wherein drawers are pushed into the makeup case and a lid of the makeup case is closed.

The broken lines illustrate portions of the makeup case. The dash-dot lines indicate the bounds of the enlarged views. None of the broken lines form part of the claimed design.
